UNITED STATES PATENT OFFICE.

WILLIAM E. PEARSON, OF BOSTON, MASSACHUSETTS.

ROTARY MOTOR.

1,042,595.

Specification of Letters Patent.

Patented Oct. 29, 1912.

Application filed February 7, 1910. Serial No. 542,580.

To all whom it may concern:

Be it known that I, WILLIAM E. PEARSON, a citizen of the United States, of Boston, in the county of Suffolk and State of Massachusetts, have invented a new and useful Improvement in Rotary Motors, of which the following, taken in connection with the accompanying drawings, is a specification.

10 My invention relates to that class of liquid motors in which the pistons are attached to a rotating piston-carrier and consists in a changeable by-pass device, by the aid of which the motor may be run equally well in 15 either direction.

The mechanism is illustrated in the accompanying drawings in which;

Figure 1 is a side elevation of the motor; Fig. 2 is a plan of the same; Fig. 3 is a 20 vertical section taken on line 3—3 of Fig. 2; Fig. 4 is an elevation, on an enlarged scale, of the by-pass valve; Fig. 5 is a cross-section taken on line 5—5 of Fig. 4.

In the drawings A, B represents the case 25 that incloses the working parts of the motor. The ports C and D are, or may become respectively inlet or outlet ports to agree with the direction which the motor is being forced to run.

30 The piston-carrier E, Fig. 3, is mounted upon the shaft S, Fig. 2, through which the energy of the motor is transmitted to the apparatus to be driven. The piston-carrier has connected to it radially sliding 35 pistons, P, P', P², P³, P⁴, P⁵, P⁶ and P⁷ arranged as shown in Fig. 3. These pistons are controlled by the disk F mounted upon the shaft F'. The shaft F' is adjustable so as to allow for the wear of the pistons and 40 is held in place by the nut F². Delivery ports C' and D' serve to conduct to or lead away from the pistons during the action of the motor.

R and R' are by-passes connecting the 45 port ways C and D to the hollow valve K. The said hollow valve K is shown on an enlarged scale in Figs. 4 and 5. This valve is constructed and mounted upon its shaft in such a manner that it may be turned by 50 the lever L', Fig. 2, acting through the shaft L so that its ports K' and K², may be

made to register with the release port K³ and by-passes R and R', as will be explained. The lever L' is provided with a latch N which engages with notches, like N', 55 made in the bracket piece M, see Fig. 2.

The operation of my motor may be explained as follows: Suppose the motor to be run in the direction from right to left, that is the driving liquid enters through the ports D, D', that is, impinges on the piston P⁴ and coacts on the piston P³ but is about to cease to have any action on said piston P³ as that piston is passing the release port K³ and the chamber between the pistons P³ 60 and P² becomes an open one, as the piston P² opens in to the delivery port C' and thence to the outlet port C. While this action is going on the ports K² and K' in the hollow valve K admit of a free passage of 65 the discharge liquid into the outlet port C. In case we wish to run the motor from left to right then the liquid comes in through ports C and C'. The hollow valve K is turned so as to cause K' to register with the 70 release port K³ and the port K² will register with the by-pass R', and the motor will be free to run in the desired direction.

A careful inspection of the arrangement 75 of the pistons, ports and by-passes and hollow valve K as above explained will show 80 that under no circumstances will there be any clogging action in the chambers between the pistons, regardless of the direction that the motor is run.

In this class of rotary motors, *i. e.* reversible, the pistons act as power generators only while passing from the delivery port to a point situated half way between the said delivery port and the full discharge 90 port, in my motor I have placed a release port at the said halfway point so that there can be no check to the free advance of the pistons after they have ceased to act as power generators and are simply passing to 95 the full discharge port and thence back to the starting point.

I claim—

A rotary liquid motor, comprising a casing having inlet and exhaust ports, a rotary 100 piston, a release port located between the inlet and exhaust ports and communicating

with the piston chamber, by-passes in communication with said inlet and exhaust ports, and a hollow cylindrical valve having ports, whereby said release port can be placed in communication with either of said by-passes.

In testimony whereof, I have signed my

name to this specification in the presence of two subscribing witnesses, on this 5th day of February A. D. 1910.

WILLIAM E. PEARSON.
